ROTATABL E OCCUPANT-PROPELLED TEETER BOARD

Jeston O. Phillips, Kansas City, Mo.

Application April 23, 1956, Serial No. 41,171

Term of patent 14 years

(Cl. D34—5)

FIG. 1

FIG. 2

FIG. 3

FIG. 4

FIG. 5

Fig. 1 is a front elevational view of a rotatable occupant-propelled teeter board, showing my new design;

Fig. 2 is a left end elevational view thereof, with the seats and foot board rotated ninety degrees from their position in Fig. 1;

Fig. 3 is a top plan view thereof, in the position shown in Fig. 1;

Fig. 4 is a bottom plan view thereof; and

Fig. 5 is an end elevational view thereof, in the position shown in Fig. 2.

The broken line showing of a supporting base in Fig. 1 is for illustrative purposes only.

I claim:

The ornamental design for a rotatable occupant-propelled teeter board, substantially as shown and described.
